UNITED STATES PATENT OFFICE.

THOMAS J. BARBOUR, OF SAN FRANCISCO, CALIFORNIA.

HOIST MECHANISM FOR MINE-SHAFTS.

SPECIFICATION forming part of Letters Patent No. 681,430, dated August 27, 1901.

Application filed December 26, 1900. Serial No. 41,124. (No model.)

To all whom it may concern:

Be it known that I, THOMAS J. BARBOUR, a citizen of the United States, residing in the city and county of San Francisco and State of California, have invented certain new and useful Improvements in Hoist Mechanism for Mine-Shafts; and I do hereby declare the following to be a full, clear, and exact description of the same.

10 The present invention relates more especially to mechanism whereby the position of the cage may be shifted or regulated as to the haulage cable or rope in accordance with the level or depth from which the dirt or ore is to be hoisted from within the mine-shaft. Ordinarily where the double-cage system is employed in connection with an endless or single haulage-cable for the raising of ore from the mine-shaft it is the custom to provide mechanism by means of which the haulage-cable may be shortened or lengthened in accordance with the length of the cable required for the hoisting of the cages from varying levels of the mine-shaft, the cages being 25 permanently attached to the cable. For instance, suppose the mine-shaft contains five working levels from which ore is taken and work is being done in the fifth level at a depth of, say, one thousand feet. It is required that one cage reach the surface or head of the shaft-compartment simultaneously with the opposing cage reaching the level of work. Now if it is desired to change from the fifth level to the fourth or third level it is required where the cages are permanently attached to the cable that the excess of cable be compensated for, so as to raise the cage within the shaft to the level required without changing the position of the surface cage. 30 This is accomplished by what is known as a "tail-take-up" mechanism, which gives a back pull upon that portion of the cable leading to the lowered cage in order to raise the said cage to the required level. By such mechanism the surface cage will reach the changed level at the same time the loaded cage reaches the surface for unloading. The auxiliary mechanism required for this purpose necessitates the outlay of considerable 45 money, and such hoist system is not adapted to the working of existing mine-shafts if timbered between compartments.

The object of the present invention is to dispense with such auxiliary take-up mechanism and provide means whereby one cage 55 may be released from the haulage-cable while the position of the opposing cage is changed to a higher or lower level within the mine-shaft.

The invention also relates to details of construction as to means for taking up the slack 60 of the cable.

In order to comprehend the invention, reference should be had to the accompanying sheets of drawings, wherein—

Figure 1 is a side view in elevation illustrating the hoisting mechanism and arrangement of the cable or rope. Fig. 2 is a top plan view of the mechanism disclosed by Fig. 1 of the drawings. Fig. 3 is a front view of the mine-shaft, disclosing the cribbing or 65 shaft-frame timbers, endless cage-rope or cable, and cages attached thereto. Fig. 4 is a similar view illustrating the running of the cage rope or cable when one cage is permanently attached thereto. Fig. 5 is an enlarged detail view, in front elevation, of one of the cages with the cage rope or cable passing through the clutch mechanisms and guide-sheaves. Fig. 6 is a similar view in side elevation. Fig. 7 is a broken detail view, in 70 side elevation, of the fixed cage illustrated in Fig. 4, said view illustrating the take-up mechanism secured to the bottom of the cage. Fig. 8 is a similar view in front elevation. Fig. 9 is a detail view of one of the clutch 75 mechanisms, partly in section; and Fig. 10 is a top plan view of the same.

In the drawings the letter A is used to indicate the frame-timbers or cribbing which divides the mine-shaft into compartments 1 90 and 2, and A² the cage or haulage rope or cable. This rope or cable runs from the drive-drum B over tension-drum B', under idler-sheave B², over pit-head sheave B³, thence down shaft-compartment 1, and under take-up 95 sheave C, thence up shaft-compartment 2, over pit-head sheave C', and thence back to the drive-drum B.

Within each shaft-compartment works or operates a cage, which cages D D' are attached 100 to the cage or haulage cable or rope in such a manner that as one cage is carried downward the other is elevated or moved upward toward the surface or head-opening of its

shaft-compartment. In Fig. 3 of the drawings the cage or haulage rope or cable is illustrated as extending around the said cages, while in Fig. 4 of the drawings the said rope 5 or cable is illustrated as attached at one end to the top of cage D, the free end passing around cage D' and being connected by a suitable take-up mechanism to the bottom of cage D. By the latter form of connection 10 one cage is rigidly or permanently secured to the cage or haulage rope or cable A², while the opposite cage is detachably secured thereto. Preferably I make each cage detachably connected to the cage or haulage rope or 15 cable and make employment of a continuous or unbroken endless rope or cable, as illustrated in Fig. 3 of the drawings. When this form of connection is employed, each cage is provided with an upper and lower 20 frame D² D³. The upper frame supports the cable-sheaves 3 4 and the lower frame the cable-sheaves 5 6. Through these sheaves the cable extends, and said sheaves are set at an angle, as illustrated in Fig. 6 of the drawings, in order that the cable or rope A² may 25 be kept clear of frame-timbers or cribbing of the shaft.

Each cage is provided with an upper clutch E and lower clutch E', which are supported, 30 respectively, by the frames D² D³. The cable or rope leads through the upper clutch E prior to passing between the sheaves 3 4 and through the lower clutch after leaving the sheaves 5 6. These clutches maintain 35 the rope or cable A² in line with the pit-head sheaves B³ C' and the guide-face of the take-up sheave C. While the sheaves 3 4 lead the cable or rope to one side of the cage, the lower sheaves 5 6 guide or return the same to the 40 center thereof. It is preferable that the cable or rope be led to one side of the cage, so as not to interfere with the loading capacity of the said cage.

In Figs. 3, 4, 5, and 6 the cage rope or cable is illustrated as passing through upper and lower guides 7 8 and the cage as held thereto by compression-screws 9 10. This is the simplest form of clutch mechanism and is mainly employed in said views to prevent 50 complication of drawings.

In Fig. 9 a detail of the form of clutch mechanism to be employed is illustrated, the same consisting of the clutch-jaws a a', connected to the collar b by the toggle-links b' b². 55 These toggle-links are forced inward and outward to open and close the clutch-jaws by the screw-rod d, which extends within the cage in order that the same may be operated from the interior or platform thereof. As the top 60 and bottom clutch mechanisms are counterparts, I have only deemed it necessary to illustrate one of the clutches.

In Fig. 4 only one cage is illustrated as being provided with the clutch mechanisms and 65 the cable or rope guiding sheaves, the opposite cage D being permanently secured to one end of the cable or rope, and the free end of

said cable or rope being attached to the chain d' of the auxiliary take-up mechanism suspended from the bottom of said cage. This 70 take-up mechanism is made use of as an auxiliary to the take-up sheave C in order that the slack of the cable or rope may be compensated for after the limit as to take-up has been reached by the take-up sheave C. The 75 take-up sheave C is secured within slide-frame C², which frame works in ways C³ in the bottom of the mine-shaft. This slide-frame C² is permitted a vertical movement of about ten feet, and the weight thereof is such 80 as to overcome that of the cable or rope A². Hence it serves to maintain the rope or cable taut and to take up such slack as may be occasioned by stretching of the cage rope or cable. After the slide-frame has reached its 85 full downward depth its usefulness as a take-up means for the slack ceases. However, the slack or stretch will seldom be so great as to overcome the limit of the take-up sheaves' play. Still to provide against such a possibility an auxiliary take-up means is employed where one cage is permanently attached to the cage cable or rope. Such mechanism is attached, preferably, to the bottom 90 of the fixed or permanent cage, and the same 95 comprises the shaft E², mounted in bearings of frame E³. To one end of said shaft is secured the worm-gear F, which is actuated by the worm F', carried by the winding-shaft F². The shaft E² carries the chain-wheel F³, 100 over which works the chain d', to which the free end of cable A² is connected. In order to operate the take-up mechanism, a crank-key is fitted over projecting end d³ of winding-shaft F². As this shaft is rotated the motion thereof is transmitted to shaft E² through the medium of the worm F' and worm-gear F.

To the drive-drum B is connected the brake-wheel G, Fig. 2 of the drawings, and larger gear-wheel G'. Motion is imparted to the 110 drive-drum B from power-shaft G², which is driven in the present case by electricity. The power-shaft works in bearings of frame G³ and has secured thereon pinion f, which meshes with gear f', secured to shaft H. To 115 said shaft is secured pinion h, which meshes with the larger gear-wheel G'.

In order to change the position of the cages D D' within the mine-shaft, so as to shift the work to varying levels, one cage is held at 120 the opening of the shaft by being supported upon chairs. (Not shown.) Its clutch mechanisms are then released in order to free the cable or rope A². When thus freed, the cage within the mine-shaft is raised or lowered to 125 the desired level. During this movement of said cage the released cage remains supported upon its chairs and the cable or rope runs freely through its guide-sheaves and clutch mechanisms. After the cage within the mine-shaft has reached the desired level the clutch mechanisms of the free cage are then operated so as to clutch or grasp the cage cable or rope firmly. The position of the cages 130

will then be one at the opening of the mine-shaft and its opposing cage at the desired level. It is only required that the chairs be removed in order that the upper or empty 5 cage be lowered while the filled or loaded cage is raised to the surface. When this cage has reached the surface, the empty cage will stand at the desired level of the mine-shaft. It will be understood that one cage ascends as the 10 opposing cage descends and that the loaded cage reaches the surface at the same time as the empty or descending cage reaches the level from which the ore is being extracted or worked.

15 Having thus described my invention, what I claim as new, and desire to secure protection in by Letters Patent, is—

1. In a single-cable hoist apparatus for mine-shafts, the combination with the endless hoisting-cable, of the opposing cable-cages, of devices carried by the cages whereby the endless cable is guided above and below the same, and means whereby the cages may be held locked to or released from the endless cable without requiring the cages to be removed from the cable in order to permit of its position being varied in accordance with the working level of the mine-shaft.

2. In a single-cable hoist apparatus for mining purposes, the combination with the mine-shaft having different levels, of the endless hoisting-cable working therein, of the cages carried thereby, of devices whereby the endless cable is guided above and below the 35 cages, and means whereby the positions of the cages may be varied upon the hoisting-cable by releasing the cable without removing the same from the guide devices.

3. The combination with the endless hoisting-cable, of the cages carried thereby, of clutch mechanisms secured to the cages and by means of which they are attached to the hoisting-cable, and means for operating the clutch mechanisms whereby the positions of 45 the cages may be varied for different working levels.

4. The combination with the hoisting-cable, of the cages carried thereby, of guide-sheaves secured to the cages and through which the 50 hoisting-cable extends, clutch mechanisms carried by the cages and by means of which the cages are locked to the hoisting-cable, and means for operating the clutch mechanisms so as to place the cages in or out of locked 55 engagement with the hoisting-cable in order that the positions of the cages may be changed in accordance with the working levels of a mine-shaft.

5. The combination with the drive mechanism, of the hoisting-cable, the pit-head sheaves over which the cable works, the take-up

sheave located within the mine-shaft for taking up of the cable slack, the opposing cages carried by the hoisting-cable, devices for guiding the endless cable above and below the 65 cages, and means whereby the relative positions of the cages may be varied upon the hoisting-cable in accordance with the working levels.

6. The combination with the endless hoisting-cable, of the shaft within which the endless cable works, the cages carried by the said cable, of guide-sheaves secured to the top and bottom portions of the cages and between which the hoisting-cable extends, and of 75 means whereby the relative positions of the cages may be varied upon the hoisting-cable so as to adjust the same to the desired working level of the shaft.

7. In a single-cable hoist apparatus for mining purposes, the combination with the mine-shaft, of the endless hoisting-cable working therein, of the cages carried thereby, one of said cages being detachably secured to the said cable, of devices for guiding the endless 85 cable above and below the said cage, and of means whereby the said cage may be released from the cable without disconnecting the cable from the guiding devices so that the relative positions of the cages may be varied 90 upon the said hoisting-cable in accordance with the working levels of the mine-shaft.

8. In a single-cable hoisting apparatus, the combination with the drive-drum, of the tension-drum, the idler-sheave, the mine-shaft, 95 the pit-head sheaves, the take-up sheave located at the bottom of the shaft, the endless hoisting-cable working over said sheaves and drums, the cages carried by the endless hoisting-cable, and means whereby the positions 100 of the cages may be varied upon the hoisting-cable in accordance with the working level of the mine-shaft.

9. In a single-cable hoisting apparatus, the combination with the mine-shaft, of the endless hoisting-cable working therein, mechanism located outside of the shaft for driving the endless cable, the opposing cages carried by the endless cable, of means for guiding the cable around the cages, and of means carried by the cages wherein the positions thereof may be varied upon the said cable in accordance with the working level of the mine-shaft.

In testimony whereof I have hereunto affixed my signature, in the presence of witnesses, this 30th day of November, 1900.

THOMAS J. BARBOUR.

In presence of—
FRANK M. LELAND,
D. J. BASSETT.
